WALL BAR OR SIMILAR ARTICLE

Emil S. Polk, Scarsdale, N. Y.

Application January 24, 1956, Serial No. 39,895

Term of patent 14 years

(Cl. D33—3)

Figure 1 is a front perspective view of a wall bar or similar article showing my new design, illustrating the bar in an open position;

The broken line showing in Figure 2 is for illustrative purposes only.

I claim:

The ornamental design for a wall bar or similar article, substantially as shown and described.
